UNITED STATES PATENT OFFICE.

KARL MODEREGGER, OF VIENNA, AUSTRIA-HUNGARY, ASSIGNOR TO
SIEMENS & HALSKE, OF BERLIN, GERMANY.

ELECTRICAL SWITCH SETTING AND LOCKING DEVICE.

SPECIFICATION forming part of Letters Patent No. 531,130, dated December 18, 1894.

Application filed February 8, 1893. Serial No. 461,414. (No model.) Patented in Germany December 6, 1891, No. 65,810, and in Austria-Hungary December 14, 1891, No. 42,614 and No. 73,712.

To all whom it may concern:

Be it known that I, KARL MODEREGGER, a subject of the Emperor of Germany, residing at Vienna, Austria-Hungary, have invented 5
5 new and useful Improvements in Electrical Switch Setting and Locking Devices, (for which I have obtained Letters Patent as follows: Austria-Hungary, No. 42,614, tom. XLI, fol. 3,887, and No. 73,712, tom. XXV, fol. 3,822, 10 dated December 14, 1891, and for which the firm of Siemens & Halske have obtained Letters Patent in Germany, No. 65,810, dated December 6, 1891,) of which the following is a specification.

15 My present invention relates to devices or apparatus designed for setting switch rails by means of an electro-motor coupled thereto and controllable from a signal box or railway station at a distant point. Special mechanism is provided for locking the switch when set by the motor.

20 The invention also embodies means and mechanism, whereby, should the switch be forced open or run through to either side by flanges of engine or car wheels, the switch rails will be at once set over fully to the main line rails toward which they were started or forced by the wheel flanges and whereby the switch rails will not remain in dangerous intermediate open positions. The normal operation and running through of the switch are also indicated at the signal box or at a central station.

25 The invention will first be described and then will be particularly defined in claims hereinafter set forth.

Reference is to be had to the accompanying drawings, forming a part of this specification, and in which similar letters and figures of 30 reference indicate like parts in the several views.

Figure 1, is a plan view of my improved electrical switch setting and locking devices; Fig. 1^a is a detail view illustrating the connection of the switch rails and their actuating bar. Fig. 2, is a central longitudinal sectional view of the same, with the main line and switch rails in transverse section. Fig. 2^a is a detail view of the coupling which permits telescoping of the switch actuating

shaft. Fig. 3, is a detail vertical sectional view showing adjustments of the locking mechanism when the switch is run through to the left hand. Fig. 4, is a detail view of the locking mechanism as it appears when the switch is operated normally by the electro-motor and thrown to the left. Fig. 5, is an enlarged detail plan view of the switch locking mechanism, and Fig. 6, is a detail view showing the action of the weighted safety lever on the locking cam in carrying the switch that has been run through fully over to the opposing main rails.

In any suitable weather-proof casing A, located outside of the main line rails 1, 1, is placed any approved form of electro-motor B, to the armature shaft of which is coupled, by two disks engaging each other by a wrist pin b, a shaft C, which is coupled to a shaft D, to which is fixed one end of a screw shaft E, 55 which in turn is connected to another shaft F, to which the switch locking mechanism hereinafter described is attached. The successive and aligned shafts C, D, E, F, are protected in a weather-proof sectional casing G, 60 which crosses the road-bed under the main line rails 1, 1, and the switch rails 2, 2. The coupling c, between the shafts C, D, is so made that while the former shaft will in rotating turn the latter one, the shaft D, may have a 65 telescoping endwise movement on the shaft C, to accommodate the motion of some parts of the locking mechanism when the switch is run through by the wheel flanges of an engine or train, and as hereinafter more fully explained.

The coupling e, between the shafts E, and F, may have any approved construction which will allow the shaft E, to turn in the shaft F, while causing both of these parts to move together endwise. As shown, this coupling consists of a sleeve keyed fast to the interior of the end of the hollow shaft F and having the reduced end portion of shaft E journaled therein. This reduced portion of shaft E 75 is slightly longer than the sleeve and has an enlarged end portion, thus permitting a slight longitudinal movement of said shaft in the sleeve. The shaft F, does not rotate, as its connection with the locking mechanism for 80

bids it. It will be understood that while the particular construction above named is preferred, any means or method of making or coupling together parts of a shaft carrying a screw E, and a non-rotatable end portion F, to connect with reciprocating parts of the switch locking mechanism, and capable of endwise telescoping action and of connection to an electro-motor or any other means whereby rotation may be given to the screw, may be adopted within the scope of my invention.

Fig. 2^a of the drawings shows one suitable coupling c having a part c' fixed to the shaft C, and a part c² fixed to the shaft D. The part c' is preferably convexed longitudinally and has opposed grooves 10, 10 which normally receive pins 11, 11, on the other part c² of the coupling. The pins, by sliding in the grooves, allow sufficient telescoping action of the shaft.

On the screw E, is fitted an internally threaded nut or traveler H, which has a lateral stud h, which moves along a side slot of the casing G, and affords means for connecting one end of a rod I, which at its other upturned or inclined end carries a transverse pin i, which gives journal bearings to three anti-friction rollers j, j, and k. The rollers j, j, engage the notched or recessed upper ends of two tappet plates or grips J, J, which are pivoted to a rigidly held shaft L, which also affords a pivotal bearing for a quadrantal guide plate K, which at its upper broader part is provided with a curved slot k', having tangential end portions k² k³, and in which slot the roller k, on the connecting rod I, has play at times during certain adjustments of the mechanism hereinafter more fully described.

On the stationary shaft L, and behind the guide K, is rigidly fixed a bearing m', to which is pivoted a catch M, having a lengthwise slot m, which receives loosely a pin N, fastened rigidly to the guide K, and whereby as said guide is rocked on the shaft L, it will carry with it the catch M, which then swings over on its journal or pivot at the bearing m', and carries with it the rod O, which has a pin o, entering the enlarged outer part of the catch slot m, and at its other end is pivoted at o', to the endwise movable switch shaft F, E, D, above mentioned.

To the lower pivoted part of the guide K, is fixed another pin P, which is shown below the horizontal plane of the guide pivot L, and has suitable pivotal connection with the heel 55 of a peculiarly formed latching cam R, having a practically heart shaped upper part consisting of two wing portions r' r², each having an eccentric outer face and providing between them an upper recess r. In this recess normally rests an anti-friction roller s, which is journaled to a lever S, fulcrumed at s', to the switch mechanism frame and carrying at its outer vertically movable end a weight T, which by its gravity tends to press the roller 60 s, into the cam latch recess r, to prevent rocking movement of the parts R, P, K, during normal shifting of the switch rails 2, 2, by

rotation of the electro-motor shaft, but allowing rocking of said parts R, P, K, when the switch is run through by the wheel flanges, 70 and as hereinafter more fully explained.

To the outer grip device J, is pivoted at u, one end of a rod or bar U, the other end or part of which is suitably coupled to the switch rails 2, 2, as seen in Fig. 1^a for shifting them 75 one way or the other for closing or opening the switch, and another rod V, which is connected at one end to the rod I, or to the coupling pin h, of the screw nut H, has at its other end any approved lever and shaft connections v, v', to electric switch devices W, and whereby suitably connected wires leading from any source of electric energy, will conduct the current to cause reverse action of the switch, operating mechanism, and whereby also the running through of the switch will be signaled at a central station.

The operation of my improved apparatus is as follows: We will suppose the switch rails 2, 2, occupy the positions shown in Fig. 2, of the drawings, and it is desired to throw them normally to the left hand. The connections V, v, to the two switches w, w, (see Fig. 1,) are adjusted relatively to the motor B, to cause rotation of the screw shaft E, in direction indicated by the arrow when the electric circuit is completed by operation of a button, key or lever at a distant signal tower or station. When the circuit is thus closed to the motor and the compound shaft C, D, E, is rotated, the nut traveler H, will be moved toward the motor along the screw E, while the entire shaft C, D, E, F, remains endwise immovable, and the rod I, is moved by and with the traveler H. The rod I, by means of its two rollers j, j, and after its third roller k, slips out of the recess k², in which it had been locked to hold the switch in the right hand position, will engage the notched grip plates J, J, and swing or rock them over toward the left hand, while the roller k, slips along in the curved slot k', of the guide plate K. During this endwise movement of the rod I, the rod U, connected to the front grip plate J, and to the switch rails 2, 2, will move the latter over to the left hand against the opposing main line rails 1, 1, and simultaneously the rod V, will by left hand endwise movement change the positions of the switch levers w, w, as the electric current to the motor is cut off 105 by the operator at the tower or station, thus leaving the motor adjusted for rotating the screw shaft E, in the reverse direction for imparting reverse motion to the switch rails when they are to be thrown back to their first 110 described right hand position at the will of the operator.

It will be understood that during the above-named normal shifting or setting of the switch rails by the action of the rotating screw shaft 120 E, the roller s, on the weighted lever S, T, by acting in the central recess r, of the cam latch R, holds or locks the guide plate K, and parts M, O, at rest in the central position, and that

on the completion of said normal left hand movement of the switch, the roller k , on the rod I, enters the notch k^3 , of the guide plate and locks the switch rails to the left hand main line rails, and the mechanism has relative positions shown in Figs. 4 and 5 of the drawings.

To normally re-set the switch rails back to the right hand opposing rails, the operator simply turns on the electric current, and the screw shaft E, then will rotate in a direction the reverse of that indicated by the arrow, and the mechanism will resume the first described positions shown in Figs. 1 and 2 of the drawings, and the electric current switching levers w, w' , will also be automatically readjusted in readiness to transmit the current to next turn the screw shaft in direction of the arrow when the switch rails are again to be set to the left hand main line rails, at the will of the operator. Another switch lever w' , is actuated simultaneously with the levers w, w , and by suitable electric connections signals the adjustments of the switch rails and mechanism at the operator's tower or station.

We now will suppose that the switch is run through by the wheel flanges of an engine or car toward the left hand from the position shown in Fig. 2, of the drawings. In this case, the screw shaft E, is not rotated and the bar U, which connects with the switch rails 2, 2, is forced to the left hand by them and carries with it the grip plates J, J, with the outer one of which the bar is connected at u .

It will be noticed from Figs. 2, and 4, of the drawings, that when the end roller k , of the rod I, is lodged in either of the portions k^2 k^3 , of the slot of the guide plate K, one wall of the top recesses of the grip plates J, lies directly against and behind the rollers j , and in front of the latter rollers there is quite a little space. It is obvious that with this construction and when the initial switch operating movement is given by the bar I, from the nut H, the roller k , on this bar will have opportunity to move forward and out of the guide plate notch k^2 , or k^3 , and into the main curved portion k' , of the slot before the rollers j, j , on the bar I, strike the opposite or farther walls of the grip plate recesses or notches to swing oversaid plates for operating the bar U, to shift the switch rails by normal action of the screw shaft. When, however, the initial movement comes by or from the switch bar U, as when the switch is run through by the car wheels, the rear walls of the recesses of the grip plates J, J, at once bite on the rollers j, j , and lock or bind the other roller k , into the notch k^2 , or k^3 , of the guide plate K, in which it rests. Consequently as the switch rails are run through by the car wheels toward the left hand, the locking of the roller k , within the notch k^2 , of the guide plate will cause the latter to be swung over by the bar U, toward the left hand with the grip plates J, J, and with the following effect: As the guide plate K, is thus swung over with the grips J, J, the pin N, fixed to the plate will, by acting in the

slot m , of the bearing M, rock the latter toward the left, thereby forcing the rod O, and the connected main shaft portions F, E, D, 70 in the same direction, while the part D, slips or telescopes over the shaft portion C, with which the electro-motor B, is directly connected. The rod I, is of course carried to the left hand also by the grip plates. This telescoping action of the shaft thus accommodates or compensates for the stationary relation of the nut traveler H, on the screw E, of the shaft during the running through of the switch. As the guide plate K, is thus thrown over toward the left hand, the pin P, on said plate will rock the cam R, to the left thereby causing the roller s , on the weighted lever S, to ride up the inner convexed wall of the right hand upper portion r' , of the cam, 80 whereby the lever will be raised until its roller s , reaches and rides over the apex of said part r' , which is the position indicated in Fig. 3, of the drawings and is taken about at the time the switch rails which have 90 been run through get their maximum movement from or by the engine or car wheel flanges. Immediately thereafter the weighted lever, while bearing by its roller s , upon the outer convexed wall of the part r' , will force 95 the cam R, farther over toward the left hand (see Fig. 6) and while the roller k , of the rod I, is locked or latched in the right hand recess k^2 , of the slotted guide plate K, and whereby as the lever S, falls, its roller s , will carry the 100 cam R, to the farthest left hand position, meanwhile causing the guide plate K, and grips J, to have like movement and thereby causing the rod U, to throw the switch rails 2, 2, which had received a partial left hand 105 movement from the engine or car wheel flanges, entirely or fully over to the opposing left hand main line rails. The operation is practically the same whether the switch be run through to the right or left hand, as the 110 form of the grips J, guide plate K, and cam R, provides for this by reverse order of movements, and the shaft portions D, E, F, may move telescopically either to the right or left hand.

It will thus be understood that with the herein described devices, the switch may be opened or closed normally by the electro-motor B, and by means of a key, lever or button shifted or touched by the operator in a 120 distant signal tower, who also will be notified by telegraph of the movements of the switch; and that should the switch be run through by a passing engine or train, the switch rails will be automatically carried over fully in 125 the same direction and against opposing main line rails, thereby avoiding dangerous intermediate open positions of the switch rails and promoting the safety of railway travel, and in this case also the operator will be telegraphically notified by or through the switch lever connections at w' , of the movements of 130 the switch.

The drawings show three binding posts or

contact plates w^2 , to the center and opposite end ones of which the switch levers w, w , are alternately adjusted to convey the electric currents as required to reverse the direction of rotation of the motor driving shaft and screw shaft; and two binding posts or contact plates w^3 , act with the lever w' , and suitably connected wires and signals to notify the operator or an attendant at a central station of the adjustments of the switch. Any other approved electric current switching devices operative from the switch rail shifting mechanism may, however, be used within the scope of my invention.

15 After the switch has been run through to the right or left hand and is carried fully over in the same direction by the action of the roller s , of the counterweighted lever S , on the left or right hand convexed faces respectively of the parts $r^2 r'$, of the cam R , the switch mechanism will be re-adjusted to normal position by raising the lever S , by hand and placing its roller s , in the central recess r , of the cam.

25 Having thus described my invention, I claim as new and desire to secure by Letters Patent—

1. In a railway switch, the combination with the switch rails, of a screw shaft, means for rotating the shaft, a nut on the screw, rocking grip plates, and rods connecting the grip plates to the switch rails and nut, substantially as described.

2. In a railway switch, the combination with the switch rails, of a screw shaft, means for rotating the shaft, a nut on the screw, rocking grip plates having recessed free ends, a rod connected at one end with the nut and engaging the grip plates at its other end, a rod connecting the grip plates and switch rails, and a guide plate provided with a curved slot having tangential end extensions and adapted to guide the connections between the nut rod and grip plates, substantially as described.

45 3. In a railway switch, the combination with the switch rails, of a screw shaft, means for rotating the shaft, a nut on the screw, rocking grip plates having recessed free ends, a rod connected at one end with the nut and engaging the recessed grip plates at its other end, a rod connecting the grip plates and switch rails, a guide plate provided with a curved slot having tangential end extensions, and connections between the nut rod and grip

55 plates, the recesses of the grip plates receiving such connections being larger than and giving play to the latter, substantially as described, whereby said connections may enter the tangential portions of the guide plate slot and be latched therein by the grip plates on movement of the latter in one direction, and whereby also the grip plate recesses permit initial movement of the connections from the tangential end portions into the main curved 60 part of the guide plate slot on movement of the grip plates in the other direction, as set forth.

4. In a railway switch, the combination with a rotatable telescoping shaft, of mechanism connected therewith for normally operating the switch by the rotation of the shaft, and means operated by the telescoping of said shaft for throwing the switch over to the opposing main line rails when run through and opened by an engine or train, substantially as described.

5. In a railway switch, the combination with a rotatable telescoping shaft, of mechanism connected therewith for normally operating the switch by the rotation of the shaft in either direction, and means operated by the telescoping of said shaft for throwing the switch over to the opposing main line rails when run through and opened by an engine or train substantially as described.

85 6. In a railway switch, the combination with a connection to the switch rails adapted to normally actuate them, of a rocking cam coupled to the connection, and a counterpoise acting on the cam, substantially as described.

7. In a railway switch, the combination with a telescoping connection to the switch rails adapted to normally actuate them, of a rocking cam coupled to the telescoping connection, and a counterpoise acting on said cam, substantially as described.

95 8. In a railway switch, the combination with the switch rails, of a telescoping revoluble shaft carrying a screw, a nut on the screw, and connections between the switch rails and the telescoping shaft and its nut, substantially as described, whereby the switch may be normally operated from the rotating screw shaft without telescoping said shaft, and whereby also the switch may be "cut open" as the shaft is telescoped endwise and without movement of the nut along the shaft, as herein set forth.

100 9. In a railway switch, the combination with the switch rails, of a telescoping revoluble shaft carrying a screw, a nut on the screw, connections between the switch rails and the telescoping shaft and its nut, a rocking cam interposed in said connections, and a counterpoise acting on said cam, substantially as described, whereby the switch may be normally operated from the rotating screw shaft without telescoping said shaft, and whereby also when the switch is "cut open" as the shaft is telescoped endwise and without movement of the nut along the shaft, the counterpoise by action on the cam will complete the throw of the switch rails to opposing main line rails, as herein set forth.

115 10. In a railway switch, the combination with the switch rails, of a telescoping revoluble shaft carrying a screw, a nut on the screw, rocking grip plates having recessed free ends, a rod connected with the nut and engaging the grip plates, a rod connecting the grip plates and switch rails, a rocking guide plate provided with a curved slot having tangential end extensions and adapted to guide and latch the connections between the nut rod and grip

plates, a pivoted catch, a rod connecting the catch to a non-rotatable part of the screw shaft, means on the rocking guide plate for actuating said catch, and means for preventing rocking of the guide plate when the switch is operated normally by or from the rotating screw of the telescoping shaft, substantially as described.

11. In a railway switch, the combination with the switch rails, of a telescoping revoluble shaft carrying a screw, a nut on the screw, rocking grip plates having recessed free ends, a rod connected with the nut and engaging the recessed grip plates, a rod connecting the grip plates and switch rails, a rocking guide plate provided with a curved slot having tangential end extensions and adapted to guide and latch the connections between the nut rod and grip plates, a pivoted catch, a rod connecting the catch to a non-rotatable part of the screw shaft, means on the rocking guide plate for actuating said catch, a pivoted cam having a central upper recess, a pin on the guide plate entering the cam, and a counter-weighted lever bearing at the central upper recess of the cam, substantially as described, whereby rocking of the guide plate and endwise telescoping action of the screw shaft is prevented when the switch is adjusted normally from the shaft, and whereby also complete lateral movement of the switch rails to opposing main line rails will be effected when the switch is "cut open" toward said main rails by the engine or car wheels, as herein set forth.

12. The combination with a railway switch comprising switch rails, a screw shaft, a nut adapted to travel along the screw, and connections between the switch rails and nut, of an electro-motor coupled to the screw shaft for rotating the same, and electric switch devices coupled with the motor and the switch rail actuating mechanism, substantially as described, whereby as the switch is set over in one direction by operation of said mechanism, the contacts will be automatically re-adjusted in readiness to reverse rotation of the screw shaft on the next passage of the current through the motor, substantially as described.

13. The combination with a railway switch, comprising switch rails, a revoluble screw shaft capable of endwise telescoping movement, a nut on the screw and mechanism substantially as specified for operating the switch normally by or from the screw shaft, and for permitting "cutting open" of the switch and subsequent full setting over in the same direction of the switch rails to opposing main line rails, of an electro-motor coupled to the screw shaft for operating the same, substantially as described.

14. The combination with a railway switch, comprising switch rails, a revoluble screw shaft capable of endwise telescoping movement, a nut on the screw and mechanism, substantially as specified, for operating the

switch normally by or from the screw shaft and for permitting "cutting open" of the switch and subsequent full setting over in the same direction of the switch rails to opposing main line rails, of an electro-motor coupled to the screw shaft for operating the same, and electric switch devices coupled with the motor and the switch rail actuating mechanism, substantially as described, whereby as the switch is set over in one direction, either normally or by being "cut open," the electric contacts will be automatically readjusted in readiness to reverse rotation of the screw shaft on the next passage of the current through the motor, substantially as described.

15. In a railway switch, the combination with the main line rails 1, 1, and switch rails 2, 2, of a laterally ranging shaft having a screw portion E, means for rotating said shaft, a nut H, on the screw, rocking grip plates J, J, a rod I, connecting the nut and grip plates, and a rod U, coupling the grip plates and switch rails, substantially as described.

16. In a railway switch, the combination with the main line rails 1, 1, and switch rails 2, 2, of a laterally ranging shaft having a screw portion E, means for rotating said shaft, a nut H, on the screw, rocking grip plates J, J, a rod I, coupled to the nut H, and carrying rollers j, j, k; a guide plate K, having a slot k' with end extensions k² k³, said slot receiving the roller k, while the grip plates receive the roller j, j, and a rod U, coupling the switch rails and grip plates, substantially as described.

17. In a railway switch, the combination with the main line rails 1, 1, and switch rails 2, 2, of a laterally ranging revoluble and telescoping shaft, comprising parts C, D, a screw E, and a non-rotatable end portion F; a nut H, on the screw, rocking grip plates J, J, a rod I, coupled to the nut H, and carrying rollers j, j, k, a guide plate K, having a slot k' with end extensions k² k³, said slot receiving the roller k, while the grip plates engage the rollers j, j; a pivoted slotted catch M, a pin N, on the guide plate K, engaging said catch, a rod O, connecting the catch M, with the part F, of the lateral shaft, and a rod U, coupling the switch rails and grip plates, substantially as described.

18. In a railway switch, the combination with the main line rails 1, 1, and switch rails 2, 2, of a laterally ranging revoluble and telescoping shaft comprising parts C, D, a screw E, and a non-rotatable end portion F; a nut H, on the screw, rocking grip plates J, J, a rod I, coupled to the nut H, and carrying rollers j, j, k, a guide plate K, having a slot k', with end extensions k² k³, said slot receiving the roller k, while the grip plates engage the rollers j, j, a pivoted slotted catch M, a pin N, on the guide plate K, engaging said catch, a rod O, connecting the catch M, with the part F, of the lateral shaft, a rocking cam R,

having a recess *r*, a counterweighted lever *S*, *T*, having a roller *s*, adapted to the recess *r*, and exterior convex faces of the cam, a connection *P*, between the parts *K*, *R*, and a rod *U*, coupling the switch rails and grip plates, substantially as described.

19. In a railway switch, the combination with the switch and main line rails, a revolute telescoping shaft *C*, *D*, *E*, *F*, a nut *H*, on the screw portion *E*, of said shaft, mechanism *I*, *J*, *K*, *M*, *O*, *P*, *R*, *S*, *T*, coupled to the nut, and a bar *U*, connecting said mechanism to the switch rails, of an electro-motor coupled to the shaft, a rod *V*, connected to the nut *H*, electric switch devices *w*, connected with the motor to reverse the current and the direction of rotation, and connections between said switch devices and the rod *V*, substantially as described, for the purposes set forth.
20. In a railway switch, the combination

with the switch and main line rails, a revolute telescoping shaft *C*, *D*, *E*, *F*, a nut *H*, on the screw portion *E* of said shaft, mechanism *I*, *J*, *K*, *M*, *O*, *P*, *R*, *S*, *T*, coupled to the nut, and a bar *U*, connecting said mechanism to the switch rails, of an electro-motor coupled to the shaft, a rod *V*, connected to the nut *H*, electric switch devices connected by the rod *V*, to the motor to reverse the current and direction of rotation; and a telegraph line 30 and electric switch device connected therewith to signal operation of the switch at a distant point, substantially as described.

In testimony whereof I affix my signature in the presence of two witnesses.

KARL MODEREGGER.
